UNITED STATES PATENT OFFICE.

HERBERT P. EWELL, OF TACOMA, WASHINGTON.

ELECTROLYTIC APPARATUS.

Application filed October 19, 1925. Serial No. 63,369.

This invention relates to electrolytic apparatuses and relates particularly to apparatuses utilizing the electrolytic decomposition of a salt in the production of an amalgam.

This application is a continuation in part of my co-pending application, Serial Number 32,323, filed May 23, 1925.

It is an object of the invention to provide an electrolytic apparatus having its electrodes arranged within a tortuous channel through which a continuous flow of the electrolyte is maintained, whereby large quantities of the electrolyte may be continuously treated within a tank of compact form.

Another object is to constantly maintain conditions most favorable to the formation of an amalgam by flowing mercury through the aforesaid channel in a direction reverse to the flow of the electrolyte.

Still another object is to associate with an electrolytic tank an auxiliary tank in communication with the electrolytic tank and containing a novel driven unit functioning to maintain a circulation of the electrolyte through the two tanks, and to churn the electrolyte in its flow through the auxiliary tank to expedite the original dissolution of a salt and to re-dissolve any portion of such salt that may precipitate out.

A further object is to conveniently mount a multiplicity of electrodes upon a frame which adapts them to be removed as a unit from an electrolytic tank and further functions as a conductor for the current energizing said electrodes.

These and various other objects the invention attains by the construction herein described and illustrated in the accompanying drawings, wherein:

Fig. 1 is a plan view of the electrolytic apparatus.

Fig. 2 is a view of the same in front elevation.

Fig. 3 is a vertical sectional view taken upon the line 3—3 of Fig. 1.

Fig. 4 is a vertical cross sectional view on the line 4—4 of Fig. 1.

In these views the reference character 1 designates a tank which in its preferred form is rectangular and of sheet metal construction, its bottom 2 being of copper or some other highly conductive metal. Baffle plates 3, rising from the bottom of said tank extend alternately from its opposite walls and thus form a tortuous or zigzag passage. Resting freely upon the plates 3 in a trans-

verse relation thereto are spaced bars 4 and secured to said bars, above the latter, are a plurality of bars 5 parallel to said plates and extending centrally above the passage 60 formed by said plates. It is preferred to form the bars 3 and 4 of copper or some other highly conductive metal. Each bar 5 supports the upper ends of two spaced rows of spaced carbon electrodes 6, the preferred form of which is cylindrical, said electrodes depending into said tank and terminating in a suitable spaced relation to the bottom 2. 7 designates ring-shaped clamping brackets which are secured to the bars 70 5 by rivets 8 (or other suitable means) and which individually receive said electrodes. Each of said brackets is engaged by a bolt 9 serving to normally close its ring firmly upon an electrode. Upon loosening of any 75 of said bolts, the rings are sufficiently expansive to free the corresponding electrodes so that the latter may readily be adjusted vertically to properly regulate the spacing of their lower ends from the copper bottom 80 2.

To one end of the tank 1 there is attached an auxiliary tank 10 which has at one end an inlet 11 to the tank 1 and an outlet 12 from the latter at its other end. Within said auxiliary tank is mounted a driven unit combining the functions of an agitator for expediting dissolution of a sodium salt as for example sodium chloride with which said tank is replenished at suitable intervals and of circulating the electrolyte at a suitable velocity through both tanks. This unit comprises a shaft 13 extending lengthwise through the auxiliary tank and journaled in blind bearings 14 upon the ends of said tank. 85 A plurality of agitator arms 15 are radially carried by said shaft and are suitably spaced both longitudinally and circumferentially of said shaft and upon an end portion of the shaft is mounted fast an impeller 16 having 100 the nature of a paddle wheel. Said impeller is opposite to the inlet 11, and when the shaft is driven, serves to force the electrolyte through said inlet from the tank 10 to the tank 1, thus establishing the circulation 105 indicated by the full line arrows in Fig. 1. Said agitator arms churn the electrolyte thoroughly in its flow through the tank 10 and expedite dissolution of the replenished salt and re-dissolve any precipitated portion 110 of the salt. It is preferred to give the bottom 17 of the tank 10 a semi-cylindrical

form so that the blades 15 may rotate in close proximity to said bottom and thus act more effectively upon the entire contents of said tank. It is also preferred to provide a 5 baffle plate 17^a extending some distance from the wall formed with the opening 11 so that the impeller may be more effective in producing a flow through said opening.

The drive connection to the shaft 13 is 10 established within the tank 10 thus eliminating any necessity for extending said shaft through a wall of said tank, with consequent risk of leakage. As shown, this drive connection is established by a chain 18 engaging 15 sprocket wheels 19 and 20, the former upon the shaft 13 within said tank and the latter upon a shaft 21 projecting above said tank. Power may be applied to the shaft 21 through a pulley 22 or other suitable drive 20 element thereon.

23 designates a generator from which an anode cable 24 leads to the bars 5 and is electrically connected through said bars to the electrodes 6, and 25 is a cathode cable 25 leading from the generator to the copper bottom 2 of the tank 1. A pipe 26, opening into said tank through its bottom, leads from a rotary pump 27 which is continuously driven from the shaft 21 by a chain 28. 30 From any suitable source said pump is supplied with mercury, the intake pipe of said pump being indicated at 29.

30 designates a discharge pipe for liquid sodium amalgam and free mercury, said pipe 35 connecting with the tank 1 through the bottom 2 in proximity to the opening 11 into said tank and leading to any suitable point of discharge. Preferably the pipe 30 discharges into the tank 1 above the normal 40 level of the electrolyte to avoid siphoning out of the mercury and sodium amalgam when the pump 27 is idle, and for a similar purpose, a trap 34 and a vent 33 are provided in the pipe 30. (See Fig. 4).

45 In the operation of the described apparatus, sufficient water is initially supplied to the tanks 1 and 10 to insure an adequate inimmersion of the electrodes 6, and a sufficient amount of sodium chloride (or some 50 other sodium salt) is fed into the tank 10 to form with such water a concentrated solution. Provision is made in any desired manner for establishing a continuous supply of mercury to the pump 29.

55 A drive is now established in any suitable manner to the generator 23 and to the shaft 21. The unit 3, 5, 6 being thus driven, a circulation of the water through the two tanks is set up and the agitator 15 throws 60 the salt into suspension in the flowing water and effects a rapid dissolution of the salt. The flow of current between the electrodes 6 and the copper bottom of the tank 1 accomplishes a decomposition of the conducting portion of the solution, and the sodium

thus released immediately unites with the free mercury to form liquid sodium amalgam which travels together with the free mercury through the tortuous passage, discharging eventually with the surplus free mercury through the pipe 30. 70

The advantage of establishing opposing circulations of the electrolyte and the mercury lies in the fact that the electrolyte is continuously losing concentration in flowing 75 through the tortuous passage, while the mercury increasingly takes the form of sodium amalgam in its flow through said passage. By opposing the two circulations, that portion of the flowing electrolyte which has the greatest concentration acts upon that portion 80 of the mercury current which has the maximum content of sodium amalgam, and the concentration of the salt compensates more or less for the contamination of the mercury 85 in maintaining an effective electrolytic action. Similarly the weakened portion of the electrolytic solution encounters relatively pure mercury and compensation is thus made for the weakening of the solution in 90 its flow through the tortuous passage.

The provision for removing all of the electrodes 6 as a unit, illustrated in dash lines in Fig. 3, facilitates inspection and cleaning 95 of said electrodes.

The described apparatus is productive of sodium amalgam at a high rate in view of the size of the complete apparatus. Thus the apparatus is peculiarly adapted for use in locations where it is necessary to conserve space, and furthermore the cost is reduced by obtaining a maximum output from an apparatus of given size. 100

By use of the described apparatus, an excess of water in the electrolyte may be avoided, and interference with the electrolytic action by crystals of the salt may be substantially eliminated. 105

Beneath the tank 10, there may be provided the illustrated heating chamber 35, having suitable inlet and outlet fittings 35^a whereby a suitable heating medium may be flowed through said chamber. 110

What I claim is:

1. In an electrolytic apparatus, a tank, means for circulating mercury through said tank, means for circulating a metallic salt in solution through said tank, counter to the flow of the mercury, and means within said tank for electrolytically decomposing said salt. 115

2. In an electrolytic apparatus, a tank, baffle members within said tank, projecting alternately from opposite walls thereof, and forming a tortuous passage, means for circulating mercury through said passage, means for circulating a metallic salt in solution through said passage counter to the flow of mercury, and means within said tank for electrolytically decomposing said salt. 120 125 130

3. In an electrolytic apparatus, a tank, baffle members within said tank, projecting alternately from opposite walls thereof, and forming a tortuous passage, means for circulating mercury through said passage, means for forming a metallic salt solution and circulating said solution through said passage, and means within said tank for electrolytically decomposing said salt.
4. In an electrolytic apparatus, a tank, means for circulating mercury within said tank, and means for forming a metallic salt solution, and means for circulating said solution through said tank, counter to the flow of mercury.
5. In an electrolytic apparatus, a tank, means for circulating mercury within said tank, means for forming a metallic salt solution, and for circulating said solution within the tank, and means for maintaining automatically a relatively constant density of said solution.
6. In an electrolytic apparatus, an electrolytic tank, electrodes operatively disposed in said tank, an auxiliary tank having a spaced inlet and an outlet in communication with said electrolytic tank, an agitator in said auxiliary tank, a propeller in said auxiliary tank and a common drive means for said agitator and propeller.
7. In an electrolytic apparatus, an electrolytic tank, a plurality of electrodes operatively disposed in said tank, an auxiliary tank having a spaced inlet to and an outlet from the electrolytic tank, a shaft mounted in the auxiliary tank, a propeller upon said shaft disposed oppositely to the said inlet, an agitator upon said shaft, and drive means for said shaft.
8. An electrolytic apparatus comprising a tank, a plurality of electrodes depending into said tank, the bottom of the tank forming a co-acting electrode, and a frame carrying said depending electrodes and forming a conductor leading to said electrodes, said frame being freely supported upon said tank and adapting said electrodes for removal as a unit.
9. An electrolytic apparatus comprising a tank, a frame extended across the upper portion of said tank, and a plurality of electrodes carried by said frame depending into said tank and individually clamped to said frame, and independently adjustable with respect to said frame to vary their relation to the tank bottom.
10. In an electrolytic apparatus, a tank for receiving the salt solution, baffle members within said tank projecting alternately from opposite walls thereof and forming a tortuous passage, means for circulating mercury through said passage, and means carried by the tank within said passage for electrolytically decomposing said salt.
11. In an electrolytic apparatus, a tank adapted to contain a quantity of mercury in its bottom portion, baffle members within said tank projecting alternately from opposite walls thereof and forming a tortuous passage, means for forming a metallic salt solution and circulating said solution through said passage, and means carried by said tank within said passage for electrolytically decomposing said salt.
12. In an electrolytic apparatus, an electrolytic tank, an auxiliary tank for receiving a salt solution, having a spaced inlet and an outlet in communication with said electrolytic tank, means within said auxiliary tank for effecting the circulation of a salt solution in said tank through the electrolytic tank by way of said inlet and outlet, means within the electrolytic tank for accomplishing electrolysis of said salt solution, and means for heating said auxiliary tank.
- In testimony whereof I sign this application.

HERBERT P. EWELL.
